UNITED STATES PATENT OFFICE

MICHAEL J. BOSEK AND WILLIAM FRANK PENDILL, OF ST. LOUIS, MISSOURI

TREEING MACHINE

Application filed July 9, 1928. Serial No. 291,443.

This invention relates to machines and devices designed particularly for the treeing of boots and shoes.

A boot or shoe is made on a last to which it is conformed, and on which it remains while the series of operations are performed on the article. After the various mechanical operations are completed it is generally necessary especially in highly skilled work, to subject the upper to a treeing operation where it is ironed and given a finishing touch. The machine used for this purpose is a treeing machine which has a tree comprising an expansible leg composed of relatively movable leg parts and a series of expansible foot parts. In order, however, to perform the treeing operation in such a machine, it is necessary to take the last out of the shoe and place the latter over the foot and leg of the tree. This not only results in a last of the shape which has been carefully preserved while the last was on the shoe, but requires that a number of different foot pieces be kept on hand.

One of the objects of this invention, therefore, is to provide means in the nature of an attachment for a treeing machine which is so constructed and adapted as to not only receive the last while remaining on the shoe and hold it firmly in position on the treeing machine leg for the treeing operation, but which is adapted for the ordinary last as used in the manufacture of shoes.

Another object is to provide a treeing machine of the character described which is simple in construction, effective in its action and economic to manufacture.

Further objects will appear from the detail description taken in connection with the accompanying drawings, in which

Fig. 1 is an illustration of the type of treeing machine embodying this invention;

Fig. 2 is an enlarged side elevation of the end of the leg;

Fig. 3 is a section on the line 3-3 of Fig. 2;

Fig. 4 is a section on the line 4-4 of Fig. 2.

Referring to the accompanying drawings 1 designates the stand or column having mounted thereon a turret 2 in which is ro-

tatably mounted a series of legs composed of relatively movable parts or members 3 and 4. Arranged within the leg is an expanding device 5 arranged to couple with a bell crank lever 6 connected by a rod 7 to a treadle which is usually raised by a strong spring. The expanding device is also acted upon by a spring 8. A strip 20 is mounted in the member 4 and to this is attached one of a series of fore parts (not shown) as usually employed in treeing machines of this type; in such a case the fore part forms a continuation of the formed heel part 30 at the end of the member 3. The parts so far described may be of any suitable or usual construction, the structure being such that the spring 8 operates on the expander 5 to yieldingly permit the members 3 and 4 and the heel and foreparts thereon to collapse when this expander is coupled with the bell crank lever 6, and the treadle depressed, the expander is operated to expand the members 3 and 4 so as to spread apart the heel part 30 and the usual fore part (not shown).

In accordance with this invention the end of the leg is formed to receive a last of any suitable or usual construction, that shown being a last composed of a heel part 10 and a forepart 11 providing a recess therebetween, the forepart having a face 12 within the recess while the heel part has a socket 13 arranged to receive the usual last pin. In order to couple the last 2 to the tree leg, the heel part 30 is provided with a bar 15 pivoted on this part and having formed therein a socket 16 adapted to receive a last pin 17. In order to secure this last pin in position the latter has a ball 18 retained within a recess therein in which is also arranged a spring 19, the edges of the recess being peened over to retain this ball in position. The last pin is thereby removably but firmly secured within the heel part 30 so as to enter the last socket 13 in order to provide a coupling for holding the last on the leg. Guided within the leg part 4 is the strip 20 having at its end a wedge 21 provided with a gripping face 22 adapted to engage the face 12 on the last forepart when the strip and wedge are within the recess between the last parts. The strip may be the

usual one now employed for attaching the fore parts to the tree as heretofore described. In order, however, to adapt it for the purpose herein described, a rib 23 on the strip engages with a groove in the wedge. A notch 24 is provided in the strip 20 for receiving a bar 25 carried by the wedge 21 and bridging the groove thereof. A plurality of aligned apertures 26 are provided in the opposite flanges 15 of the groove in wedge 21 for removably receiving pin 27. The pin 27 is disposed to ride upon the upper surface of rib 23 and may be placed in any selected pair of aligned apertures 26 in order to vary the inclination of 10 the wedge 21 so that the device may be readily adapted to receive lasts of different sizes. With this construction the wedge can be removable and adjustable but firmly secured on 15 the strip.

20 In order to place a last with a shoe thereon in operative relation with the tree leg, the last is placed on the pin 17. The strip 20 is then moved into the recess between the last parts so that a gripping face 22 of the wedge 25 will engage the face 12 on the last forepart. This is done while the expander is in retracted position and with the leg members contracted. Upon depression of the treadle the same will operate on the expander to spread 30 the members 3 and 4 apart; this will move the pin 17 relative the strip or element 20 so as to secure the coupling between the last and the tree leg and firmly hold the latter in position. The shoe can now be ironed as usual.

35 This ironing can even extend to the top of a high boot, it can extend over the leg parts 3 and 4. It will be seen that the provision of the wedge, which can be placed to any extent within the recess, there can be a lost motion 40 before the faces 22 and 12 engage; this lost motion can be used to expand the members 3 and 4 to conform to the top of a high boot. After the shoe has been ironed the last can be taken off by contracting these members.

45 It will, therefore, be seen that the invention accomplishes its objects. A treeing machine is provided which is adapted to receive the last as ordinarily used in the manufacture of boots and shoes. It is, therefore, not necessary to take the shoe off the last but the treeing and ironing operations can be performed even on high top boots while the latter remains on the last. The structure is such that it is readily adapted to any type treeing machine with the minimum of alterations.

55 Moreover, the treeing machine may still be used by removing the couplings 17 and 21, (which are complete and self-contained and removable as a whole from the leg members) 60 and by attaching the usual fore-parts.

It will be understood that while the particular embodiment shown and described, is to a knuckle hinge last, the invention is susceptible of employment to other types and forms of last. It will, furthermore, be under-

stood that certain features and sub-combinations are of utility and may be employed without reference to other features and sub-combinations. That is contemplated by and is within the scope of the appended claims. It is, therefore obvious that various changes may be made in details of construction within the scope of the appended claims, without departing from the spirit of this invention. It is, therefore, to be understood that this invention is not to be limited to the specific details shown and described.

Having thus described the invention what is claimed is:

1. A treeing machine comprising, a leg, a last, and a complete last coupling which as a whole is removably attached to the end of said leg and adapted to removably receive said last.
2. A treeing machine comprising, a leg having a socket, a last having a socket, and a complete self-contained coupling removably engaging said leg and last sockets.
3. A treeing machine comprising a leg having a socket, a last, a last coupling engaging said socket and adapted to removably receive said last, and yielding means for removably retaining said coupling in said socket.
4. A treeing machine comprising, a leg, a last provided with a fore-part having a recess providing a coupling-engaging face, and a coupling removably attached to the end of said leg and adapted to enter said recess for engaging said face.
5. A treeing machine comprising, a leg having a part extending therebeyond, a last provided with a fore-part, having a recess providing a coupling-engaging face, and a coupling removably attached to said part and adapted to enter said recess for engaging said face.
6. A treeing machine comprising, a leg having a part extending therebeyond, a last having a recess providing a coupling-engaging face, a coupling engaging said part and adapted to enter said recess for engaging said face, and yielding means for removably retaining said coupling on said part.
7. A treeing machine comprising, a leg composed of relatively movable parts, a last having coupling-engaging parts, and couplings removably engaging said last parts and removably attached to said leg parts.
8. A treeing machine, comprising, an expandable leg composed of relatively movable members, one of said member having a formed heel part and the other member being adapted to receive a fore-part, a last having a heel part and a fore-part, and means for removably coupling said last to the end of said leg.
9. A treeing machine, comprising, an expandable leg composed of relatively movable members, one of said members having a

formed heel part and the other member being adapted to receive a fore-part, a last having a heel part and a fore-part, and means for removably coupling the heel of said last to the heel part of one of said members.

10. A treeing machine, comprising, an expandible leg composed of relatively movable members, one of said members having a formed heel part and the other member being adapted to receive a fore-part, a last having a heel part and a fore-part, means for removably coupling the heel of said last to the heel part of one of said members, and

15 a coupling on the other of said members adapted to engage the fore-part of said last.

11. A treeing machine, comprising, an expandible leg composed of relatively movable members, one of said members having a formed heel part and the other member being adapted to receive a fore-part, a last having a heel part and a fore-part, and an adjustable coupling on one of said members for engaging the last whereby to adapt the

25 leg to receive lasts of different sizes.

In testimony whereof we affix our signatures this 7th day of June, 1928.
